PAPERMAKING APPARATUS

John A. Rosmalt, Appleton, Wis., assignor to D. J. Murray Manufacturing Co., Wausau, Wis., a corporation of Wisconsin

Application February 14, 1945, Serial No. 577,864

8 Claims. (Cl. 92—44)

1

The present invention relates generally to improvements in the art of manufacturing paper from fibrous pulp, and relates more specifically to improvements in the construction and operation of apparatus for distributing and mixing the pulp stock and for controlling the flow thereof through and from the head box of a Fourdrinier type of paper making machine.

The primary object of my invention is to provide various improvements in the construction and operation of fibrous pulp mixing and feeding equipment for use in the head boxes of paper making apparatus, whereby the rapid production of better paper is made possible.

It has heretofore been customary in the manufacture of paper with the aid of Fourdrinier types of paper making machines, to provide so-called distributor or rectifying rolls in the head boxes of such machines, these prior rolls usually comprising rotating perforated cylinders disposed both in the final pass and at the delivery end near the slice inlet of each head box. While it has also been proposed to substitute revolving structures having perforated radial vanes, for the more generally used drum type distributor rolls, all of these prior devices were constructed in a rather crude manner of relatively heavy and comparatively rough metals, thus making them costly to fabricate, difficult to handle during installation and removal, and impossible to maintain in clean condition and free from objectionable fibre accumulation, besides preventing them from effectively mixing and distributing the pulp during normal use. In order to insure most effective mixing and uniform distribution of the fibres prior to delivery of the pulp to the slice inlet of the Fourdrinier wire, the distributing devices whether of the drum or vaned type, must be smooth and devoid of fibre collecting corners and projections throughout, since any pits of irregularities to which fibres may cling temporarily and from which compact masses of fibre may subsequently be periodically released, will obviously result in non-uniformity and malformation of the sheets and possible subsequent disruption or breakage thereof. Then too, in order to prevent objectionable deflection of the distributing devices for machines having relatively wide head boxes and Fourdrinier wires, it is necessary to construct the prior rolls of heavy metal thus

2

making them cumbersome to handle during insertion and removal while effecting wash-ups and cleaning of the paper making installations; but in spite of these various objections the operators have continued the use of this antiquated equipment for many years.

It is therefore a more specific object of my present invention to provide improvements in flow mixing and distributing devices for the feed 10 or head boxes of such paper making machines, which will substantially eliminate all of the objectionable features of prior equipment of this kind and will thereby facilitate the production of superior paper at higher speeds than are possible with the prior mechanisms.

Another specific object of this invention is to provide an improved system of mixing rotors adapted for use in successive flow passages through the head box of a Fourdrinier machine, whereby most efficient homogeneous mixing and distribution of the fibres throughout the entire area of the stream of stock as it approaches the slice inlet, is definitely assured at all times regardless of the speed at which the machine is 20 being operated.

A further specific object of the invention is to provide an improved mixing rotor assemblage and journal support therefor, whereby the rotor may be quickly and conveniently installed or 30 removed for inspection or cleaning, while also being devoid of objectionable deflection during normal operation.

Still another specific object of the present invention is to provide an improved flow mixer 35 which is simple and durable in construction, which may be formed of relatively inexpensive smooth surfaced material in a manner which will positively eliminate objectionable local accumulation of fibre masses, and which is built 40 to insure most effective mixing of pulp during normal use.

An additional specific object of my invention is to provide an improved mixing rotor structure, which may be assembled in sections to produce 45 rotors of diverse standard lengths, and which may be easily repaired at moderate cost in case a section thereof should be accidentally damaged.

Another additional specific object of this invention is to provide various new and useful improvements in pulp mixing rotors for paper

making machines, whereby the construction, manipulation, and operation thereof is facilitated, while the efficiency is augmented to the maximum and the maintenance cost is reduced to a minimum.

These and other specific objects and advantages of the invention will be apparent from the following detailed description.

A clear conception of the various features constituting my present improvement, and of the construction and operation of numerous types of mixing rotors built in accordance with the invention, may be had by referring to the drawings accompanying and forming a part of this specification wherein like reference characters designate the same or similar parts in the various views.

Fig. 1 is a somewhat diagrammatic vertical section taken longitudinally through the surge tank, flow spreader, head box, and a fragment of the Fourdrinier wire of a paper making machine, showing a transverse section through the improved flow mixers associated with the head box;

Fig. 2 is a transverse section through the head box of the assemblage shown in Fig. 1, taken along the line 2—2 and looking toward the mixing rotors;

Fig. 3 is a fragmentary greatly enlarged central longitudinal section through the driving end and one of the removable bearings of a typical embodiment of my improved mixing rotor, also showing a fragment of the adjacent head box wall in section;

Fig. 4 is a somewhat reduced part sectional elevation of the opposite end portion of the three-piece four blade mixing rotor assemblage shown in Fig. 3;

Fig. 5 is a transverse vertical section through the mixing rotor of Fig. 4, taken along the line 5—5;

Fig. 6 is another transverse vertical section through the same rotor, taken along the line 6—6 of Fig. 4;

Fig. 7 is still another transverse vertical section through the same mixing rotor, taken along the line 7—7 of Fig. 4;

Fig. 8 is a somewhat enlarged end view of a one-piece four vane mixing rotor embodying the invention, and adapted to cooperate with removable end bearings such as shown in Fig. 3;

Fig. 9 is a transverse vertical section through the one-piece rotor of Fig. 8 taken medially thereof;

Fig. 10 is a similarly enlarged end view of an eight vane seven-piece mixing rotor also embodying the invention, and especially adapted for cooperation with removable journal bearings such as shown in Fig. 3 and for use adjacent to the final outlet of the head box;

Fig. 11 is a transverse vertical section taken medially of the ends thereof, through another eight vane mixing rotor adapted for use adjacent to the slice inlet, and formed of seven pieces;

Fig. 12 is a smaller elevation of a fragment of the main spanning piece of the rotor of Fig. 11, showing an end thereof applied to one of the end supporting shafts;

Fig. 13 is a fragmentary elevation of one end portion of another type of four vane mixing rotor embodying the invention, and comprising a number of end coacting vane sections and intervening connecting members;

Fig. 14 is a transverse vertical section through

the mixing rotor of Fig. 13 taken between two successive vane connecting members;

Fig. 15 is an end view of one of the vane connecting members of the rotor shown in Figs. 13 and 14, showing the central tension bolt in section;

Fig. 16 is another fragmentary elevation of one end portion of still another four vane type of the improved mixing rotor, comprising a number of overlapping and directly united end coacting sections;

Fig. 17 is a transverse vertical section through a mid-section of the rotor of Fig. 16, taken intermediate the ends of the section;

Fig. 18 is still another fragmentary elevation of an end portion of a further modified four vane sectional flow mixing rotor, the sections of which have transverse cross-sections similar to that of Fig. 17;

Fig. 19 is an elevation of the major portion of a four vane rotor having the vanes thereof twisted in opposite directions proceeding from the opposite ends thereof toward the center; and

Fig. 20 is another elevation of the major portion of still another four vane twisted rotor having the vanes thereof twisted helically in the same direction from one end of the rotor to the other.

Although the present disclosure has been confined to four and eight vane mixing rotors provided with special axially removable end shafts and bearings and formed primarily of light material such as plastic, it is not my desire or intention to unnecessarily limit the invention or to restrict its utility by virtue of the embodiment of all or several of these features in a single assemblage.

Referring especially to Figs. 1 to 7 inclusive of the drawing, the paper making machine illustrated therein comprises in general a surge tank 21 normally communicating with the pulp screens of a paper making installation and having a lower discharge opening which communicates with a flow spreader 22; a Fourdrinier wire 23 of any suitable width coacting with a breast roll 24 and being provided with a slice inlet 25; a head box 26 interposed between the discharge end of the spreader 22 and the slice inlet 25 and having therein several transverse partitions 27 coacting with side walls 28 to form successive oppositely directed passes for the pulp 29 normally flowing through the box; a four vane relatively large diameter mixing rotor 30 spanning and being rotatable within the final pass 31 of the head box 26; and an eight vane mixing rotor 32 of smaller diameter spanning and being rotatable in the outlet end of the head box 26 directly adjacent to the slice inlet 25.

While some of this apparatus is of rather well known construction, it is noteworthy that in the assemblage shown in Figs. 1 and 2, the initial mixing rotor 30 which is located in the vertical portion of the final pass 31 of the head box 26 is provided with only four vanes and is of considerably larger diameter than the eight vane final mixing rotor 32 which is disposed near the slice inlet 25 of the Fourdrinier wire 23, and this difference between the rotors 30, 32 is an important feature of my present invention for reasons which will hereafter be set forth more in detail. The opposite side walls of the head box 26, are ordinarily provided with suitable smooth liners 33 as shown in Fig. 3, and the rotors 30, 32 may be of diverse types but are both preferably rotatably and removably sus-

pended from the side walls 28 of the head box 26 by means of aligned end shafts 34, 35 and special bearing assemblages 36 associated with these shafts. The shafts 34 which project outwardly beyond the adjacent bearing assemblages 36, are the driving shafts and may be provided with suitable driving sheaves or sprockets 37 as indicated in Fig. 2, and these driving sprockets 37 may be keyed or otherwise detachably connected to the protruding shaft ends.

The improved shaft and bearing assemblage 36 associated with each end of each mixing rotor 30, 32, is shown in detail in Fig. 3, and comprises a bearing housing 38 having an integral tubular end 39 snugly fitting a bore in the adjacent wall 28 and being firmly but detachably secured to this wall by means of cap screws 40; a rotor supporting shaft 34 or 35 disposed concentric with the bores of the housing 38 and having a polygonal end portion 41 slip fitted within the adjacent similarly polygonal end socket 42 of the rotor 30, each supporting shaft also being provided with a cylindrical bearing portion 43 and with an integral circular flange 44 disposed between the portions 41, 43 thereof; a self-lubricating guide bearing 45 formed of graphite or the like, and coacting with the cylindrical portion 43 adjacent to the flange 44, this bearing 45 being snugly fitted within the smallest bore of the housing 38; a self-aligning ball bearing 46 interposed between the supporting shaft and the housing 38 outwardly beyond the cylindrical shaft portion 43 and being held in place by a nut 47 and an outer cap 48; a pair of sealing rings 49, 50 coacting with the shaft portion 43 between the bearings 45, 46 and being spaced apart by a spacing sleeve 51; and leakage drainage passages 52 formed in the housing 38 and sleeve 51 for conducting liquid which escapes past the bearing 45 from the assemblage.

In the bearing assemblages 36 which coact with the outwardly protruding driving shafts 34, the end cap 48 is provided with an additional packing ring 53, but these rings 53 may be omitted from the end caps 48 coacting with the opposite end shafts 35 which may be closed to conceal these shafts; and in both cases the caps 48 are detachably secured to the adjacent housings 38 by cap screws 54. By providing such a bearing assemblage 36 at each end of each rotor 30, 32, these rotors may be quickly and conveniently released from their supporting shafts 34, 35 by merely removing the cap screws 40 and by thereafter sliding the released assemblages axially away from the intervening rotors until the polygonal shaft portions 41 have been completely withdrawn from the adjacent rotor sockets 42. The released rotors 30, 32 may then be lifted freely from within the head box 26, and reassembly of the rotors and their supporting assemblages 36 may obviously be just as quickly and conveniently effected.

The rotors 30, 32 which are preferably formed of light but durable material having smooth surface finish, such as plastic, may be constructed in various ways in accordance with my present improvement, and in the improved typical rotor structure specifically illustrated in Figs. 3 to 6 inclusive, the four vane rotor assemblage comprises three pieces, namely, a flat main flight or vane 55 formed integral with both end sockets 42, and a pair of aligned auxiliary flights or vanes 56 disposed perpendicular to the main vane 55 and being firmly secured thereto by means of several rod rivets 57, all of the vanes

55, 56 extending throughout the full length of the rotor 30. The main vane 55 is centrally rigid but is preferably provided with a series of holes 58 of relatively large diameter spaced uniformly throughout the wing portions thereof, while the auxiliary vanes 56 are cut away at the center of the rotor and are pierced by series of uniformly spaced smaller holes 59; and these holes 58, 59 as well as all other portions of the rotor assemblage, are provided with rounded corners and are devoid of fibre collecting pockets and projections. The auxiliary vanes 56 are also thickened at the points of penetration thereof by the rivets 57, in order to avoid weakening of the vanes; and the end portions of these vanes 56 are also slip fitted into parallel grooves 60 formed in the end sockets 42, so as to enhance the rigidity of the rotor 30.

In cases where the rotors 30 are not exceptionally long, these four vane rotors may also be formed of one piece of material as depicted in Figs. 8 and 9 wherein the four similar radiating vanes 61 are formed integral with the end sockets 42 and alternate vanes 61 are provided with large and small openings or holes 58, 59 uniformly spaced throughout the areas thereof. The square or otherwise polygonal socket 42 of this modified one-piece four vane rotor 30 are cooperable with the similarly polygonal inner end portions 41 of supporting shafts 34, 35 in the manner previously described, and this unitary type of rotor assemblage should likewise be devoid of fibre collecting projections and corners and should have smooth surface finish throughout. The unitary construction of the rotor 30 of Figs. 8 and 9 obviously provides a strong assemblage in which there are no parts which could possibly become loose and dislodged from the others.

The smaller eight vane rotors 32 may also be built in various ways, either without a cross member formed integral with the opposite end sockets 42, or with an integral cross-connection as shown in Figs. 10, 11 and 12. In the embodiment of Fig. 10, the spaced end sockets 42 of the eight vane rotor 32, are provided with aligned series of parallel recesses 62, and the radial vanes 63 have their ends snugly fitted within these recesses 62 and rigidly secured to the sockets 42 in any suitable manner. The successive vanes 63 are provided with large and small openings 58, 59 respectively, spaced throughout the areas thereof, and this rotor 32 should also be devoid of sharp edges upon which fibres are likely to accumulate. As specifically shown in Figs. 11 and 12, the opposite end sockets 32 are formed integral with a main flight or vane 64 having large openings 58 therein, and being provided with bosses 65 having openings therethrough disposed at 45° angles and perpendicular to the plane of the main vane 64; and auxiliary inclined and perpendicular vanes 66, 67 are secured to the main vane 64 at the local bosses 65 by means of rod rivets 57 passing through the boss openings. The perpendicular vanes 67 should also be provided with large openings 58, while the inclined vanes 66 should be provided with smaller openings 59 throughout their areas; and the opposite ends of the auxiliary vanes 66, 67 may be snugly fitted within parallel aligned recesses 62 in the end sockets 42 as in Fig. 10.

The rotors 30, 32 if of great length, may also be built up of a number of aligned and end connected sections as illustrated in Figs. 13 to 18

inclusive. In the embodiment of Figs. 13, 14 and 15, the rotor 30 comprises a series of aligned four-vane sections 68, 69 each having four integrally united vanes radiating from a common axis; and a series of cross-shaped connecting members 70 having cross-grooves 71 for snugly receiving the ends of the sections 68, 69. The end sections 68 are formed integral with the end sockets 42 which are cooperable with the polygonal portions 41 of the adjacent shafts 34, 36, and all of the sections 68, 69 may be joined by a central tension bolt 72 extending axially through the rotor. The vanes of the successive sections 68, 69 are preferably provided with large and small holes 58, 59 as shown; and all edges of the sections 68, 69 and of the cross-members 70 should preferably be rounded, while the surfaces thereof should be as smooth as possible. Any desired number of similar intermediate sections 69 and connecting members 70 may be utilized, depending upon the length of rotor desired, and this type of sectional rotor may be utilized in both the four and eight vane assemblages. The connecting members 70 may be riveted to the adjacent ends of the blades which are confined within the cross-grooves 71, or they may be otherwise united to provide a rigid rotor structure.

In the embodiment of Figs. 16 and 17, the rotor 30 comprises a series of aligned four-vane sections 73, 74 each of which also has four integrally united perforated vanes radiating from the rotor axis; these sections having overlapping adjacent ends 75 firmly united by rivets 76. The end sections 73 are formed integral with the supporting end sockets 42, and a tension bolt 72 also extends centrally through and additionally unites the sections 73, 74 to form a sturdy rotor 30. In the specific embodiment of Fig. 18, the rotor 30 also comprises a series of aligned four-vane sections 77, 78 each having four integral perforated vanes radiating from the central rotor axis; but alternate sections 78 of this rotor have end cross-grooves 79 therein formed to snugly receive the ends of the adjacent and intervening rotor sections. The ends of the coating sections 77, 78 are likewise firmly united by rivets 76 and a tension bolt 72 is again utilized to additionally unite the aligned sections. The vanes of all of the rotor sections 73, 74, 77, 78 may be provided with large and small holes 58, 59, and any desired number of similar sections may be utilized in either the four or eight vane type of rotor 30, 32, in an obvious manner.

More effective distribution of the pulp being acted upon by the mixing rotors 30, 32 may also be obtainable by providing twisted or helical vanes as specifically shown in Figs. 19 and 20. In the embodiment of Fig. 19, I have shown a four vane rotor 30 having four radiating vanes twisted in opposite directions from the end sockets 42 toward the center. This rotor 30 comprises a main twisted vane 80 integrally united with the opposite end supporting sockets 42, and a pair of auxiliary twisted vanes 81 secured to the opposite sides of the main vane 80 by transverse rod rivets 57 and having their inner end portions fitted within parallel recesses 60 formed in the end sockets 42. In Fig. 20, I have shown a four vane rotor 30 having four radiating vanes twisted helically in the same direction throughout their entire lengths, and this rotor comprises a main twisted vane 82 formed integral with the opposite end sockets 42, and a pair of auxiliary twisted vanes 83 secured to the opposite sides of the main

vane 82 by transverse rod rivets 57 and again having their end portions snugly fitted within parallel recesses 60 formed in the end sockets 42. The vanes 80, 81, 82, 83 of these twisted vane rotors are again provided with holes 58, 59 preferably covering the major areas thereof, and should likewise be devoid of sharp pockets and corners upon which fibres might accumulate.

When constructing an installation in accordance with my present invention, it is preferable to provide a rotor 30 of relatively large diameter and having relatively few vanes, in the final pass 31 of the head box 26, and to also provide a rotor 32 of relatively smaller diameter but having a greater number of vanes near the slice inlet 25. The reason for providing such different rotors 30, 32 at the two locations, is so that the pulp will be rather gently agitated and thoroughly mixed in the larger upwardly directed conduit of the final pass 31, and will be more rapidly agitated and thoroughly mixed as it leaves the slice inlet leading to the Fourdrinier wire 23. During normal operation of the paper making machine the rotors 30, 32 should be constantly rotated in the direction indicated by the arrows in Fig. 1, by application of driving power to the sprockets 37 shown in Fig. 2, and the pulp flowing through the head box 26 will obviously be constantly and thoroughly mixed especially as it leaves the final pass 31 of the head box. The vanes of the rotors 30, 32 should however be provided with holes 58, 59 in order to avoid undesirable obstruction to the flow of the pulp, and these openings should preferably be arranged as shown in the various rotors, that is, with successive vanes having perforations of different sizes therein, in order to additionally enhance the agitating and mixing action of the rotors without undesirably obstructing the flow past these rotors. While the straight vane rotors will ordinarily effectively perform their functions, it may be desirable to cause the pulp to flow back and forth with respect to the side walls 33 of the head box 26 as it passes these rotors, and this action can be gently produced by providing twisted vane rotors such as shown in Figs. 19 and 20. In relatively narrow head boxes 26 it may be preferable to utilize one-piece rotors such as shown in Figs. 8 and 9, but in the case of longer rotors, the construction thereof may be facilitated either by providing main and auxiliary vanes as in Figs. 4, 5, 6, 10, 11, 12, 19 and 20, or by providing sectional rotors such as shown in Figs. 13 to 18 inclusive. In all cases, the rotor assemblages 30, 32 are made readily insertable and removable by utilizing detachable bearing assemblages 36, such as shown in detail in Fig. 3, and the rotors 30, 32 should also preferably be formed of relatively light material such as plastic and should have smooth surfaces throughout and be devoid of sharp corners and projections which might tend to cause the fibres to cling thereto.

From the foregoing detailed description it will be apparent that my present invention provides an improved flow mixing and distributing system for the head boxes of paper making machines, whereby continuous and uniform treatment of the pulp is assured at all times, and wherein the various passages and parts are readily accessible for inspection and cleaning. The use of successive rotors 30, 32 of different diameters having a different number of mixing vanes or paddles and perforations of different sizes, enhances the mixing effect and insures uniform distribution of the fibres throughout the entire width of the slice

inlet, thereby avoiding the production of weak spots and unevenness in the slice even when the machine is operating at high speed. The formation of the rotors 30, 32 of light but durable material such as plastic, and the provision of the outwardly releasable end supports and bearing assemblies 36, facilitates removal and insertion of the rotors when the head boxes 26 have been emptied; and the provision of journal assemblies having both guide bearings 45 and self-aligning bearings 46 associated with the adjacent stub shafts 34, 35, serves to effectively compensate for slight deflections while still maintaining the end shafts and the intervening rotors in proper alignment at all times.

In accordance with the invention, the rotors 30, 32 may obviously be formed in one piece, of several readily united parts, of end unitable sections of any desired length, or of twisted vane construction, in order to most effectively meet various operating conditions. While the one-piece structure positively eliminates loose parts; the three-piece four vane rotors of Figs. 4, 19 and 20, and the seven-piece eight vane rotor of Figs. 11 and 12 may be readily manufactured and firmly assembled to produce strong and durable structures. The sectional rotor structures of Figs. 13 to 18 inclusive may be advantageously utilized to produce rotors of various lengths from stock sections; while the twisted vane rotors of Figs. 19 and 20 have the advantage of working the pulp stream laterally so as to insure perfect distribution of the fibres throughout the entire flow area. The smooth formation of these rotors 30, 32 with rounded corners and devoid of pockets, is important in order to eliminate local fibre accumulations, and the use of perforations 58, 59 of different sizes properly applied to the successive vanes is also important in order to enhance the effectiveness of fibre distribution throughout the pulp stream. It is also noteworthy that in the improved assemblage, the removable rotors are located in the head box 26 out of vertical alignment with each other, so that each of these rotors may be freely independently removed without disturbing the other. The improved rotors 30, 32 should in all cases be properly operated so as to avoid excessive turbulence in the stream, and the simplicity of these rotor assemblies obviously permits their manufacture at moderate cost.

It should be understood that it is not desired to limit this invention to the exact details of construction or to the precise mode of operation, herein shown and described, for various other modifications within the scope of the appended claims, may occur to persons skilled in the art.

I claim:

1. A flow mixer for a paper making machine, comprising, a pair of members provided with axially aligned sockets each having a supporting shaft coacting therewith, and a plurality of longitudinally twisted perforated vanes interposed between and secured to said members, said vanes radiating from a common axis and being uniformly helically twisted in opposite directions relative to said axis and proceeding from said sockets toward the medial vane portions.

2. A flow mixer for a paper making machine, comprising, a pair of members having coaxial sockets each having a supporting shaft coacting therewith, and a longitudinally twisted vane interposed between and interconnecting said mem-

bers, said vane radiating from the common axis of said sockets and being helically twisted in opposite directions about said axis proceeding from said sockets toward the medial vane position.

3. A flow mixer for a paper making machine, comprising, a pair of end members having coaxial sockets each having a supporting shaft coacting therewith, each of said members also having external grooves therein and extending longitudinally thereof on opposite sides of its socket, a longitudinally twisted vane firmly uniting said members between said grooves, and other longitudinally twisted vanes slip fitted within said member grooves and coacting with the opposite sides of said first mentioned twisted vane.

4. A flow mixer for a paper making machine, comprising, a pair of end members having coaxial sockets each having a supporting shaft coacting therewith, each of said members also having external grooves therein and extending longitudinally thereof on opposite sides of its socket, a longitudinally twisted vane firmly uniting said members between said grooves, and other longitudinally twisted vanes slip fitted within said member grooves and coacting with the opposite sides of said first mentioned twisted vane, all of said vanes radiating from the common axis of said sockets and being helically twisted in opposite directions about said axis proceeding from said sockets toward the medial vane portions.

5. A flow mixer for a paper making machine, comprising, a pair of members provided with coaxial polygonal sockets each having the similarly polygonal end of a supporting shaft slip fitted therein, each of said members also having external grooves therein on opposite sides of its socket, a main vane rigidly uniting said members between said grooves and extending across the common axis of said sockets, and auxiliary vanes slip fitted within said grooves and being secured to the opposite sides of said main vane.

6. A flow mixer for a paper making machine, comprising, a pair of spaced members provided with coaxial sockets and each having external longitudinal grooves on opposite sides of its socket, a supporting shaft coacting with each of said sockets and being removable axially therefrom, a main vane rigidly uniting and spanning the space between said members and extending across the common axis of said sockets, and auxiliary vanes having end portions fitted within said grooves and being secured to the opposite sides of said main vane.

7. A flow mixer for a paper making machine, comprising, a pair of spaced members provided with coaxial sockets and each having external longitudinal grooves on opposite sides of its socket, a supporting shaft coacting with each of said sockets and being removable axially therefrom, a main vane rigidly uniting and spanning the space between said members and extending across the common axis of said sockets, auxiliary vanes having end portions slip fitted within said grooves and spanning said space on the opposite sides of said main vane, and means for firmly connecting the medial portions of said auxiliary vanes to adjacent local portions of said main vane.

8. A flow mixer for a paper making machine, comprising, a pair of spaced members having coaxial polygonal sockets and each being provided with diametrically opposite external grooves, a pair of coaxial supporting shafts each having a

2,440,727

11

polygonal end slip fitted into one of said sockets and being axially removable therefrom, a main vane integrally uniting and spanning the space between said members and extending across the common axis of said sockets between said grooves, and auxiliary vanes having end portions slip fitted within said grooves and also having medial portions secured to the adjacent opposite side portions of said main vane.
